KETCHUP RAKE

Stanley F. Burnidge, Elgin, Ill.

Application August 18, 1948, Serial No. 148,175

Term of patent 7 years

(Cl. D44—29)

To all whom it may concern:

Be it known that I, Stanley F. Burnidge, a citizen of the United States, residing at Elgin, Illinois, in the county of Kane and State of Illinois, have invented a new, original, and ornamental Design for a Ketchup Rake, of which the following is a specification, reference being had to the accompanying drawing, forming a part thereof, in which:

Fig. 1 is a side elevational view of a ketchup rake, showing my new design;

Fig. 2 is a side elevational view taken at right angles to Fig. 1;

Fig. 3 is a top plan view taken on the line 3—3 of Fig. 1;

Fig. 4 is a bottom view taken on the line 4—4 of Fig. 2; and

Fig. 5 is a sectional view taken on the line 5—5 of Fig. 2 looking in the direction indicated by the arrows.

I claim:

The ornamental design for a ketchup rake, substantially as shown.

STANLEY F. BURNIDGE.
